UNITED STATES PATENT OFFICE

151,309

DESIGN FOR AN OSCILLATING ELECTRIC FAN TYPE HEATER

Samuel A. Witte, Chicago, Ill., assignor to Witte
Mfg. & Sales Co., Chicago, Ill., a firm

Application July 3, 1947, Serial No. 140,091

Term of patent 14 years

(Cl. D81—10)

To all whom it may concern:

Be it known that I, Samuel A. Witte, a citizen of the United States, residing at Chicago, in the county of Cook and State of Illinois, have invented a new, original, and ornamental Design for an Oscillating Electric Fan Type Heater, of which the following is a specification, reference being made to the accompanying drawing, forming a part thereof and in which:

Fig. 1 is a perspective view of an oscillating electric fan type heater, showing my new design; and

Fig. 2 is a rear perspective view thereof with the casing rotated to a different position.

The heater is so constructed that both sides thereof are substantially alike.

I claim:

The ornamental design for an oscillating electric fan type heater, substantially as shown and described.

SAMUEL A. WITTE.
